UNITED STATES PATENT OFFICE.

FREDERICK MERTSHEIMER, OF DENVER, COLORADO, ASSIGNOR OF ONE-HALF TO I. H. CONGDON, OF OMAHA, NEBRASKA.

SPARK-ARRESTER.

SPECIFICATION forming part of Letters Patent No. 328,962, dated October 27, 1885.

Application filed June 29, 1885. Serial No. 170,154. (No model.)

To all whom it may concern:

Be it known that I, FREDERICK MERTSHEIMER, of Denver, in the county of Arapahoe and State of Colorado, have invented certain 5 Improvements in Spark-Arresters for Locomotives, of which the following is a specification.

This invention relates to an improved construction and arrangement of parts for arresting and extinguishing sparks in locomotive-boilers and discharging the resulting cinders while the engine is in motion, the present arrangement being designed more particularly as an improvement upon that upon which Letters Patent of the United States were granted to me on the 22d day of July, 1884, No. 302,513.

In the accompanying drawings, Figure 1 represents in side elevation the forward portion of a locomotive having my invention incorporated therein. Fig. 2 is a vertical longitudinal section through the center of the same. Figs. 3, 4, and 5 are transverse vertical sections on the lines $x\ x$, $y\ y$, and $z\ z$, respectively, looking in the directions indicated 25 by the arrows.

With the exception of the peculiarities hereinafter described, the locomotive may be of ordinary construction in all its parts.

In carrying my invention into effect the 30 outer shell or body of the boiler is extended forward a considerable distance in advance of the tube-sheet a to form a smoke-box, and to the top of this box, at the forward end, I apply the smoke-stack c . At the forward end 35 of this extension of the smoke-box I secure to its under side a cinder-chamber, D , extending downward, its bottom inclining downward toward the middle, and also inclining forward to a discharge-pipe, E , which is extended 40 therefrom in a lateral direction in order to deliver the cinders at the side of the road outside of the rails. I prefer to arrange this pipe, as shown, to deliver in advance of the truck or pilot wheels; but it may be otherwise located, if preferred. The cinder-chamber D opens 45 at the top throughout its entire area into the smoke-box, there being no obstruction whatever between them.

In the smoke-box, immediately in advance

of the tube-sheet, I locate a transverse deflecting or draft-regulating plate, d , having a forward inclination toward the lower edge. This plate is of a width or diameter somewhat less than that of the smoke-box, so that the products of combustion may flow in a forward direction around its outer edge. It may be fixed 50 in position; but I prefer to provide for its vertical adjustment, in order to meet the varying conditions encountered in practice. A simple means of adjustment (represented in the drawings) consists of two vertical rods, e , attached to the edges of the plate, and extended upward through collars or plates at the top of the smoke-box, and secured by external set-screws, f ; but other equivalent adjusting devices, such 55 as are within the knowledge of the skilled mechanic, may be substituted.

In front of the plate d , I locate within the smoke-box a perforated plate, g , commencing at or near the top of the smoke-box and extending in a downward and forward direction to a point near the front, where it is joined to the lower edge of a second perforated plate, h , which extends upward and forward until it meets the front of the smoke-box at or near 70 the top forward of the smoke-stack. The two plates g and h are joined at their edges to the walls of the smoke-box, and constitute jointly a screen or septum, through which all products are compelled to pass in flowing to the 75 stack.

The exhaust tubes or nozzle i are extended forward and upward through plate g to a point immediately beneath the stack, as usual. The perforations of the plates g and h are elongated 80 horizontally, as represented in the drawings. They may be modified in size; but in practice I find that good results are obtained by openings three thirty-seconds of an inch by one-half inch in size.

Practical experience has shown that the elongation of the openings horizontally instead of vertically is of great practical advantage, in that there is less liability of their becoming choked or clogged by the accumulation of 95 cinders therein. Thorough practical tests have shown that when the plates are inclined from the perpendicular and the openings elong-

gated horizontally the cinders arrested by the surface of the plate will be deflected downward across the narrow or smaller diameter of the openings without tendency to lodge there-
5 in, while in the case of openings which are elongated vertically the cinders will frequently pass through the same or accumulate therein.

Owing to the inclined positions of the plates, 10 and the extended area which they present, the aggregate area of the openings may be so great that the plates afford practically no impediment to the draft, the exhaust and delivery being as free, or nearly so, as in ordinary 15 boilers.

From the boiler-head, or other suitable source whence water may be received under pressure, I extend a pipe, *k*, forward to the bottom of the cinder-chamber *D*, where it is 20 divided into two arms or branches, one terminating in the bottom of the chamber and the other extended forward into the delivery-pipe *E*. This pipe, provided with a suitable cock under control of the engineer, serves as 25 a means of delivering water upon the cinders, for the double purpose of wetting them down to extinguish the fire and delivering them forcibly from the chamber *D* through the pipe *E* when desired. The outer end of the pipe 30 *E* is preferably, but not necessarily, provided with a valve for closing its mouth. This valve may be of any proper construction; but I recommend for the purpose the device represented in the drawings, consisting simply of a 35 plate, *f*, hinged to swing across the same. The pivot is encircled by a spiral spring, which causes sufficient friction between the parts to keep the valve from opening accidentally, and prevents chattering. The lower edge of the 40 valve may be interlocked, as shown, with a lip on the mouth of the pipe to hold the parts in close contact. The valve will be connected by rod *m* and elbow-lever *n* or other proper connecting devices with a rod, *o*, extending 45 backward within reach of the engineer, so that he may open and close the valve from his post of duty while the engine is in motion.

In the operation of the boiler the sparks and cinders passing forward through the flues or 50 tubes encounter the rear surface of the plate *d*, by which they are arrested and directed downward. Passing the edges of the plate, the smoke and gaseous matters flow upward through the perforations in the plates *g* and 55 *h* to the stack, while the solid matters arrested by the said plates fall into the chamber *D*.

At suitable times the engineer opening the 60 cock, causes water to be discharged through the pipe *k*, whereby the cinders are thoroughly extinguished, and the remaining fire, if any, extinguished. At proper times the attendant, by means of the operating devices, opens the valve *f*, whereupon the delivery-water being continued through the pipe *k*, the accumulated 65 cinders will be delivered through the pipe *E* and discharged by the roadside.

By means of my apparatus the cinders may

be delivered at will without the necessity of shutting off steam or stopping the engine, and this without impairing or appreciably interfering with the draft through the boiler-tubes. 70

To afford access to the internal parts without the necessity of removing the plates *g* and *h*, I provide the smoke-chamber with a man-hole and cover, *t*, at the top, as shown in Figs. 75 1, 2, and 3. I also provide in the side of the cinder-chamber *D* a man-hole and cover, *u*, as shown in Figs. 1 and 5.

Having thus described my invention, what I claim is— 80

1. In combination with the boiler having a forward smoke-chamber, the perforated cinder-arresting plates and the imperforate deflector-plate *d*, suspended in rear of said plates in position to permit the passage of the smoke 85 around its entire periphery.

2. The boiler having the forward smoke-chamber and the perforated plates therein, in combination with the inclined plate *d*, located between the flues and the perforated 90 plates, and combined with means, substantially as described, for effecting its adjustment bodily in a vertical direction.

3. In a spark-arrester, the combination, 95 with a boiler having a forward smoke-chamber, of an inclined plate or plates located in said chamber and provided with openings or perforations elongated in a horizontal direction, substantially as and for the purpose described. 100

4. In a spark-arrester for locomotives, a cinder-arresting plate arranged obliquely to the path of the outgoing products, substantially as described, whereby the cinders are caused to cross the openings in the direction 105 of their lesser diameter and thus prevented from lodging therein.

5. In a locomotive-boiler, a cinder-arresting plate inclined downward and forward and provided with openings elongated horizontally, substantially as and for the purpose described. 110

6. In combination with a locomotive-boiler, an inclined perforated plate located in its forward end to arrest cinders and deflect the 115 same downward, and the cinder-chamber built on the under side of the boiler beneath the plate and having its upper side in free communication with the boiler throughout its entire width. 120

7. In combination with a locomotive-boiler, an inclined perforated plate to arrest the cinders, a cinder-receiving chamber at the base, and a discharge-pipe extending laterally from said chamber to deliver the cinders outside of 125 the track.

8. In a locomotive-boiler, the combination, with a cinder-arresting chamber and plates for directing the cinders thereto, of the discharge-pipe and a water-delivery pipe extended into said discharge-pipe, substantially 130 as described, whereby the automatic delivery of the cinders is effected.

9. In a locomotive-boiler, a cinder-arresting

chamber and spark-arresting devices, substantially as shown, to direct the cinders thereto, in combination with the delivery-pipe E, the water-pipe discharging into said chamber, and the water-pipe discharging into the delivery-pipe.

- 10 10. In combination with a locomotive-boiler having a spark-arresting chamber at the front, a laterally-extending discharge-tube, in combination with a valve to close said pipe, and means, substantially as described, for operating said valve from a distance, and a water-delivery pipe to effect the discharge of the cinders when said valve is open.
- 15 11. In combination with a locomotive-boiler having the smoke-chamber at its forward end,

two perforated plates, g and h, located beneath the stack or chimney and approaching each other toward the lower edges.

12. The locomotive-boiler provided with 20 the spark-arresting plates g and h, fixed in position, with the man-hole plate t, affording access to the smoke-chamber in rear of the perforated plates.

In testimony whereof I hereunto set my 25 hand, this 18th day of May, 1885, in the presence of attesting witnesses.

FREDERICK MERTSHEIMER.
